(57) **CLAIM**

The ornamental design for an end panel for a storage cabinet
 or the like, as shown and described.

DESCRIPTION

FIG. 1 is an isometric view of an end panel with molding for
 a storage cabinet or the like incorporating our new design;
 FIG. 2 is a front elevation view thereof;
 FIG. 3 is a side elevation view thereof; and,
 FIG. 4 is a top plan view thereof.

The broken lines are for illustrative purposes only and form
 no part of the claimed design.
